US00D701680S

(12) **United States Design Patent**
Della Valle et al.

(10) **Patent No.:** **US D701,680 S**
(45) **Date of Patent:** **** Apr. 1, 2014**

(54) **SHOE**

(75) Inventors: **Andrea Della Valle**, Sant'Elpidio a Mare (IT); **Marco Censi**, Milan (IT); **Guillaume Marie Claude Hinfray**, Milan (IT)

(73) Assignee: **Tod's S.p.A.**, Sant'Elpidio a Mare (Fermo) (IT)

(**) Term: **14 Years**

(21) Appl. No.: **29/422,638**

(22) Filed: **May 22, 2012**

(30) **Foreign Application Priority Data**

Nov. 24, 2011 (EM) 001952540

(51) **LOC (10) Cl.** **02-04**

(52) **U.S. Cl.** **D2/902; D2/944**
USPC .....

(58) **Field of Classification Search**

USPC ..... D2/896, 902, 906, 907, 908, 909, 910, D2/911, 912, 929, 943, 944, 945, 947, 951, D2/953, 954, 960, 969, 970, 972, 973, 976, D2/977, 978; 36/83, 113, 114, 115, 126, 36/127, 128, 129, 130, 131, 136, 137, 3 A, 36/3 B, 25 R, 30 R, 32 R, 45, 50.1, 57

(57) **CLAIM**

The ornamental design for a shoe, as shown and described.

DESCRIPTION

FIG. 1 is a front elevational view of a shoe showing our new design;

FIG. 2 is a rear elevational view thereof.

FIG. 3 is a left side elevational view thereof.

FIG. 4 is a right side elevational view thereof.

FIG. 5 is a top plan view thereof.

FIG. 6 is a bottom plan view thereof; and,

FIG. 7 is a perspective view thereof.

The ornamental design which is claimed is shown in the drawings, wherein the dashed lines in FIGS. 1-7 represent stitching.

1 Claim, 6 Drawing Sheets
